No. 83,702.

PATENTED NOV. 3, 1868.

J. FALLOWS.
BEER COOLER

Kitme 8803:
Bryg Monsson
J. B. Knobley

JAMES FALLOWS, OF PHILADELPHIA, PENNSYLVANIA, ASSIGNOR
TO HIMSELF AND JOHN PFEIFER.

Letters Patent No. 83,702, dated November 3, 1868.

IMPROVED BEER-COOLER.

The Schedule referred to in these Letters Patent and making part of the same.

To all whom it may concern:

Be it known that I, JAMES FALLOWS, of the city of Philadelphia, in the State of Pennsylvania, have invented a new and useful Cooler for Beer and other beverages on draught; and I do hereby declare that the following is a full, clear, and exact description of the construction and operation of the same, reference being had to the accompanying drawing, making a part of this specification, in which the letters marked thereon indicate the different parts referred to herein.

The object of my invention is to afford a portable cooler, which can be hung upon the faucet of a beer-cask, or otherwise be supported upright, so that, when a measure of the liquid is drawn from the cask, or poured into the mouth of the cooler, it will pass rapidly down through the cooler, and be discharged from the same, by gravitation, into any suitable receiving-vessel, in the cooled condition desired in such beverages.

My invention consists, substantially as hereinafter described, in the combination of a vessel filled with clean pebbles, or coarse, hard gravel-stones, with an ice-holding case, in such a manner that a small measure of beer or other beverage can be run or poured into the mouth of the vessel containing the pebbles of stone, and be rapidly discharged from the latter, by gravitation, in the cooled condition desired for drinking.

Referring to the drawing, A B is the ice-holding case, C D the pebble-holding vessel, and E the pebbles or coarse gravel-stones contained therein.

The case A B is about seven inches high, and four and a half inches in diameter, (inside,) cylindrical in form, and has a lid, a', hinged to its upper end, for admitting of the introduction of lumps of ice, b', into the case.

The vessel C D is also cylindrical in the form of its body, and is about two inches in diameter, and five inches long, with tapering ends, c' and d', and is secured rigidly, in a vertical position, in the centre of the cylindrical case A B, by means of the tapering upper end, c', which extends upward a short distance through the centre of the upper end of the case A B, and a tube, d', which is fixed to the lower end, d', of the vessel C D, and extends horizontally or radially out through the side of the case A B, and near its lower end.

The outer end of the said tube d' has a stop-cock, F, attached, so as to discharge downward.

The vessel C D is filled with clean, hard pebbles or

large gravel-stones, E, introduced through the open upper end, c', and, adjusted in the upper end, c', there is a wide-mouthed tunnel, G.

The operation of this cooler, when supplied with the ice, b', and suspended, by its bail a", from the faucet of a beer-cask, as indicated by the faint lines x y, or otherwise supported vertically, is as follows:

The ice keeps the pebbles E nearly as cold as itself, and, consequently, when a small measure, say a half-pint glass or mug, of the beer or other beverage is run or poured into the tunnel G, it will pass rapidly down in contact with and between the cold pebbles E and the inner sides of the vessel C D, through the latter, and thence through the cold horizontal tube d' and open cock F, as indicated by the arrows, in a condition, acquired mainly from the cold pebbles, as cold nearly as the ice itself; and, during the necessary though short intermission between the successive draughts, the said pebbles recover their previous cold temperature, and thus are capable of producing the same cooling-effects successively.

The case A B, in this instance, is shown as made of sheet-metal, and single, but it may be made with double walls, like the common water-cooler, or it may be coated with felt, in order to better preserve the ice, if so desired.

The vessel C D should be made of sheet-metal, of single thickness.

The apparatus is simple and inexpensive of construction, and is also both economical and effective in its cooling-operation, especially as a cooler for beer in draughts.

I wish it to be understood that I do not desire nor intend to confine myself, in the construction of this cooler, to any particular material, nor to the size or proportions given; but, having fully described my invention, and its mode of operation,

What I claim as new, and desire to secure by Letters Patent, is—

A portable cooler, consisting of a vessel, C D, filled with pebbles, coarse gravel-stones, or their equivalents, in combination with an ice-holding case, A B, the same being constructed and arranged to operate together, substantially as and for the purpose described.

JAMES FALLOWS.
